UNITED STATES PATENT OFFICE,

SAMUEL B. JEROME, OF NEW YORK, N. Y.

DESIGN FOR A CLOCK-CASE.

SPECIFICATION forming part of Design No. 15,559, dated November 18, 1884.

Application filed September 16, 1884. Term of patent 7 years.

To all whom it may concern:

Be it known that I, SAMUEL B. JEROME, a resident of New York, in the county of New York and State of New York, have invented and produced a new and original Design for a Clock-Case, of which the following is a full description, in connection with the accompanying photograph, which represents a face view of my new design for a clock-case.

5 The body A of the clock-case is in the accompanying photograph represented in form

of a book, the cover of which has cell-like depressions *a a*, as shown, which are arranged about the dial B.

I claim—

15 The design for a clock-case, the same consisting of the body A, having ornaments *a*, and dial B, substantially as shown.

SAMUEL B. JEROME.
